UNITED STATES PATENT OFFICE

ARBA VAN WORMER, OF FORT WAYNE, INDIANA, ASSIGNOR TO HORTON MANUFACTURING COMPANY, OF FORT WAYNE, INDIANA, A CORPORATION OF INDIANA.

STOP MECHANISM FOR WRINGERS.

1,105,225.

Specification of Letters Patent. Patented July 28, 1914.

Application filed June 3, 1912. Serial No. 701,129.

To all whom it may concern:

Be it known that I, ARBA VAN WORMER, a citizen of the United States, and a resident of Fort Wayne, in the county of Allen and State of Indiana, have invented certain new and useful Improvements in Stop Mechanism for Wringer; and I do hereby declare that the following is a full, clear, and exact description thereof, reference being had to the accompanying drawings, and to the letters of reference marked thereon, which form a part of this specification.

This invention relates to improvements in stop mechanism for wringers and the like and consists of the matters hereinafter described and more particularly pointed out in the appended claims.

The invention herein is shown as applied to a wringer used on a washing machine of a well known type comprising a tub with a hinged lid for holding the clothes and water and a beater or dolly mounted on a shaft depending from the lid into the tub and adapted to be given a rotary, oscillatory movement. The gearing for operating the dolly forms no part of the present invention, the same being described and claimed in a patent granted to me on the 10th day of September, 1912, Number 1,038,239. The wringer is of familiar type and is attached to the fixed top of the tub at one side of the hinged lid and the operating mechanism is capable of driving the operating shaft of said wringer continuously in either direction.

Referring now to the drawings:—Figure 1 is a view representing a top plan of a washing machine provided with a wringer driven by my improved reversing mechanism. Fig. 2 is a view representing that part of my reversing mechanism located at the end of the wringer which is toward the front of the tub and including the lever or arm for controlling the reversing mechanism. Fig. 3 is a like view showing the parts in a different position. Fig. 4 is a view representing a vertical section through the parts shown in Fig. 2, in a plane indicated by the line 4—4 of Fig. 2. Fig. 5 is a view representing the wringer and the reversing mechanism in side elevation and partially in vertical section. Fig. 6 is a view representing a vertical section through Fig. 5 in a plane indicated by the line 6—6 of Fig. 5.

Referring now to that embodiment of my invention illustrated in the drawings, 10 indicates a washing machine tub of familiar construction having a hinged lid 11, a fixed top part 12 to which the lid is hinged and a fixed top part 13 located at one side of the hinged lid and extending at right angles to the fixed part 12. Said fixed part 13 is adapted for the attachment of a wringer 14.

15 indicates an operating shaft extending in a direction at right angles to the vertical plane of the wringer 14 and adapted to be driven, as shown in the drawings, by a large gear 16 which meshes with the pinion 17 on the hub of a large fly-wheel or pulley 18 that is power driven. The outer end of the shaft 15 has bearing in an upright arm 19 rising from a bearing plate 20 attached to the side of the tub.

21 indicates a second operating shaft extending parallel to the operating shaft 15 and adapted through a segmental gear 22 to impart a rotary oscillatory movement to a beveled pinion 23 which is fixed to the top of the dolly shaft. The connections between the gear 16 and the shaft 21 are such as to change the continuous rotary movement of the gear 16 into a rotary oscillatory movement of the operating shaft 21. In the particular construction of gearing illustrated, means is also provided, as in the construction described in the application referred to, for actuating the gearing by hand power if desired.

As before pointed out the part of the mechanism for operating the dolly shaft forms no part of my present invention as claimed herein and the further description thereof will be unnecessary.

24, 25 indicate the rolls of the wringer 14. One of said rolls, as shown in the drawings, the lower roll 24, has a shaft 26 which is prolonged beyond the wringer frame and has bearing in a casing 27 located at the rear end of the wringer frame and attached to the wringer board 13.

28 indicates a gear fixed on the shaft 26 and in mesh with a gear 29 mounted on a horizontally extending stud made rigid with the wall of the casing 27. Said gear 29, as shown in the drawings, is made integral with a bevel gear 30, placed in an adjacent plane in front of it and adapted for engagement with either one of two beveled pinions 31, 32 that are fixed on a shaft 33 and con-

stitute the reversing gears of the mechanism. Said shaft 33 extends in a horizontal plane at right angles to the central axis of the stud 30 and in axial alinement with the operating shaft 15. Said shaft 33 has endwise and rotative bearing in end plates 34, 35 of the casting 27 and is coupled to the shaft 15 in such manner as to rotate therewith. As shown, a sleeve 36 is keyed to the end of the shaft 15, said sleeve having beyond the shaft 15 diametrically opposite longitudinally extending slots 37, 37. The end of the shaft 33 slidingly engages within the sleeve 36 and is provided with a pin 33^a, the projecting ends of which engage in said slots 37, 37, so as to prevent a relative rotation between the shaft 15 and the shaft 33 while at the same time permitting a longitudinal movement of the shaft 33 with reference to the shaft 15.

On the shaft 33 intermediate the beveled gears 31, 32, is mounted a sleeve 38 in which said shaft has rotative bearing. The sleeve is held from endwise movement on the shaft by reason of the engagement of its ends against the reversing gears 31, 32. Said sleeve 38 has a vertical flat face 39 on its side toward the end of the wringer and is provided with a projecting pin 40 which engages within a vertical slot 41 in a rock-arm 42 that is keyed to the end of a shaft 43. Said shaft 43 is located below and extends parallel to the wringer shaft 26. It projects at each end beyond the wringer frame where it has bearing in upright plates 44, 45 that are located adjacent to the ends of the wringer frame and are preferably bolted both to the wringer frame and to the wringer board thereby producing a very rigid construction. It is apparent that by rocking the shaft 43 endwise movement may be imparted to the shaft 33 carrying the beveled reversing gears 31, 32 so as to bring either of said gears into mesh with the idle pinion 30 and thus produce a rotation of said pinion and with it the wringer roll in either direction. When the rock-arm 42 is in its intermediate position neither of the gears 31, 32 will be in mesh with said idle gear 30 and the wringer rolls will remain at rest.

At the front end of the wringer there is secured to the rock-shaft 43 adjacent the upright bearing plate 45, a rock-arm 46.

47 indicates a swinging controlling lever which is located in a plane intermediate the bearing plate 45 and the rock-arm 46 is fulcrumed in any convenient manner on said bearing plate 45. The fulcrum of said lever 47 is located below the top of the rock-arm 46 which is provided with a radially extending slot 48 in which engages a pin 49 carried by the lever 47. The lever 47 has a crank-handle 50 for convenience in operating it. It is apparent that by swinging the lever 47 in either direction, the engage-

ment of its pin 49 in the slot 48 of the crank-arm 46 will cause said crank-arm 46 to be swung to the left or to the right according to and corresponding to the direction in which the lever 47 is swung. Thus by 70 swinging the lever 47 either of the reversing gears may be brought into mesh with the idle gear 30. In the intermediate vertical position of said lever, the reversing gears will be in an inoperative position.

In order to lock the rock-arm 46 in position when either of the reversing gears are in engagement with the idle gear 30, the following construction is provided: 51, 52 indicate stops located at each side of and below the level of the fulcrum of the controlling lever 47. Said stops are preferably made adjustable in a vertical direction and are adapted to limit the swinging movement of the lever 47 in either direction. As shown, 80 said stops are in the form of set-screws which are threaded through off-sets 53, 53, on the upright bearing plate 45. By adjusting said screws the lever 47 is stopped in that position in which the gears have been brought 90 into proper mesh, and the parts are so proportioned relative to the total endwise movement of the reversing gears in moving from operative position to the other that the pin 49 will pass below the level of the fulcrum 95 of the lever 47. Thus any tendency to rotate the rock-shaft 43 and the rock-arm 46 to disengage the reversing gears will be resisted since such rotation would act to rotate the pin 49 through the lower shorter arc 100 of a circle described about the said fulcrum and this is resisted by the stops 51, 52. In other words, the pin 49 is caused to pass below the dead center when the reversing gears are brought to operative engagement and the lever arm is held in position until force is used to raise said lever sufficiently for said pin to pass above said position. Such construction is simple and effective for the purpose intended and does away with the necessity for spring dogs or catchers to retain the controlling lever in operative position.

The operation of the reversing mechanism will be readily apparent from the above description.

In order to provide for a quick and as nearly as may be automatic release in case the fingers should be caught between the rolls of the wringer, I provide the following mechanism: The bearing plates 45, 44 are extended upwardly beyond the level of the top wringer roll, as clearly shown in Fig. 5 and are there provided with bearings for a horizontal rock-shaft 54 located in the vertical plane of the wringer. At 115 each side of the top wringer roll and on a level slightly above the horizontal plane containing the line of contact of the wringer rolls are located horizontal bars 55, 55, which are suspended by links 56 from cross- 120 125 130

bars 54⁴ fixed to the rock-shaft 34. At the end of the shaft 54, vertically above the lever 47 is secured a rocking member or bar 57. 58, 59 indicate rods hung from the ends of said bar 57 and having hooks 59 at their lower ends. Said hooks 59 extend through suitable slots 60, 60, in the bearing plate 45 into the plane of the lever 47. When the lever arm 47 is in a position corresponding to the position of the rock-shaft 42 in which one or the other of the reversing gears are in mesh with the idle gear 31, a rocking movement of the shaft 54 in a direction to raise the link 58 which is on the side of said lever 47 will cause the hooked end 59 of the link to raise the lever arm 47 and lift it beyond the dead point. As shown in the drawings, the links 58 pass loosely through apertures in the rocking bar 57 and are threaded at their ends above said bar to receive nuts 58² by means of which the length of said links below the bar may be properly adjusted. The downward swing of the bar with reference to a link has no effect on that link as it simply slides through the aperture in the bar. A vertical leaf spring 61 is secured to suitable tags 62 formed on the face of the bearing plate 45 in the plane of the longitudinal median line of the lever arm 47 when it is in its intermediate vertical position. The upper end of said leaf-spring 61 is engaged between pins 63 on said lever. Thus movement of the rock-arm 46 in either direction is resisted by the leaf-spring 61.

The operation of the safety device is as follows: When the lever arm 47 is shifted into its dead position to bring one or the other reversing gear into mesh with the idle pinion 30, the movement is yieldingly resisted by the spring 61. While said lever 47 is in the position indicated in Fig. 3 corresponding to the operative position of one of the reversing gears, the spring has no effect to bring the rock-arm 46 back into its vertical position, but rather tending to hold the parts more firmly in the position shown, as will be readily understood. In this position the hooked end 59 of one of the links 58 is engaged below the lever arm. Should the operator in manipulating the wringer or in passing the clothes between the rolls thereof get his or her fingers caught between the rolls, his natural upward movement of his hand and fore-arm in an attempt to withdraw his fingers, will cause his hand to strike the associated horizontal bar 55, thereby lifting the link 58 sufficiently to raise the lever 47 beyond its dead point. The spring 61 will then instantly complete the movement of the rock-arm 46 and bring it into its intermediate position with the reversing gears in inoperative position. The rotation of the wringer rolls will thus be automatically stopped.

The advantage of the use of a safety ap-

pliance of the character described in connection with the rolls of a wringer is apparent. Said rolls being in the nature of feed rolls act to draw the fingers when once caught between them with irresistible force, so that the instant stopping of the rolls is the only way to divorce a hand from it. The improved safety appliance is adapted only to instantly throw the automatically starting operating member into its operative connection with the rolls, but the trigger member, in this case, one of the links 58, is so arranged that the natural upward movement of the one whose finger or finger tips are caught, trips the trigger, so that the feed rolls are stopped almost before the hand has time to cry out.

While in describing my improved safety appliance I have shown it in connection with a preferred form of reversing mechanism and controlling mechanism for the same in which the lever which shifts the reversing gears is raised through an angle of more than 90 degrees, i.e., bringing the reversing gears from an inoperative position to an operative position, or in other words is shifted beyond a dead center, thus securing as before described the necessary separate locking devices, it will be understood that my invention in this respect is not limited to such a construction, device for locking the reversing gears.

The reversing mechanism shown herein is claimed in a divisional application, filed Jan. 7th, 1913, Number 781,902, the claims now originally relating to said mechanism having been canceled from this case.

I claim as my invention:

1. In combination with oppositely rotative elements, means for activating said elements, including a continuously rotating member adapted for operating said elements and movable from an inoperative to an operative position, a rock-arm for providing movement of said continuously rotating member, a lever having a pin and slot connection with said rock-arm for rocking the same, a stop adapted to limit the movement of said lever when said continuously rotating member reaches its operative position, said stop being positioned to arrest said lever when it has passed a dead center, a trigger member, means adapted for connecting said trigger member to said lever to move said lever beyond the dead center when said trigger member is struck, and means for automatically returning said continuously rotating member to its inoperative position when said lever has passed dead center.
2. In combination with oppositely rotative elements adapted to be operated in either direction, means for activating said elements including reversing gears, an idle gear adapted to be engaged by one or the other

of said reversing gears, and a continuously rotating connecting member movable in either direction from an inoperative intermediate position to an operative position, a controlling member for moving said continuously rotating member, trigger members located at each side of said elements and means acting to move said continuously rotating member from an operative to its inoperative position when one of said trigger members is struck.

3. In combination with oppositely rotative elements adapted to be operated in either direction, means for actuating said elements including reversing gears, an idle gear adapted to be engaged by one or the other of said reversing gears, and a continuously rotating connecting member movable in either direction from an inoperative intermediate position to an operative position, a controlling member for moving said continuously rotating member, yielding means tending to resist the movement of said continuously rotating member from its inoperative to an operative position, means for locking it in either operative position, triggers located at each side of said elements, and mechanism intermediate said trigger members and said locking means for releasing the locking means when either of said trigger members is struck.

4. In combination with oppositely rotative elements adapted to be operated in either direction, means for actuating said elements including reversing gears, an idle gear adapted to be engaged by one or the other of said reversing gears, and a continuously rotating connecting member movable in either direction from an inoperative intermediate position to an operative position, trigger members located at each side of said ele-

ments, means tending to return said continuously rotating member to its inoperative position, means for locking said continuously rotating member in an operative position, and mechanism intermediate said trigger member and said locking means for releasing the locking means when either of said trigger members is struck.

5. In combination with oppositely rotative elements adapted to be operated in either direction, means for actuating said elements including reversing gears, an idle gear adapted to be engaged by one or the other of said reversing gears, and a continuously rotating connecting member movable in either direction from an inoperative intermediate position to an operative position, a rock-arm for producing movement of said continuously rotating member, a lever having a pin and slot connection with said rock-arm for rocking the same, a stop adapted to limit the movement of said lever when said continuously rotating member reaches an operative position, said stop being positioned to arrest said lever when it is on a dead center, trigger members located at each side of said elements, means adapted for connecting each of said trigger members to said lever to move said lever beyond the position of dead center when said trigger member is struck, and means for automatically returning said lever to its intermediate position after it has passed the dead center.

In testimony, that I claim the foregoing as my invention I affix my signature in the presence of two witnesses, this 29th day of May A. D. 1912.

ARBA VAN WORMER.
